CONCRETE JOINT SHAPING TOOL

Herman W. Davis, Pollock Pines, Calif., assignor
to A. Teichert & Son, Inc., a corporation of
California

Filed Oct. 30, 1968, Ser. No. 14,228

Term of patent 14 years

Int. Cl. D8—02

U.S. Cl. D8—45

FIG-1

FIG-2

FIG-3

FIG-4

FIG-5

FIGURE 1 is a top plan view of a concrete joint shaping tool showing my new design;

FIGURE 2 is an end elevational view, the opposite end being substantially similar in appearance;

FIGURE 3 is a front elevational view;

FIGURE 4 is a bottom plan view; and,

FIGURE 5 is a rear perspective view.

I claim:

The ornamental design for a concrete joint shaping tool, as shown and described.
